US0D1102242S

(12) United States Design Patent (10) Patent No.: US D1,102,242 S
(45) Date of Patent: * Nov. 18, 2025

(54) CUP HOLDER

(71) Applicant: Jiangmen Jiushang Home Furnishings Co., Ltd, Jiangmen (CN)

(72) Inventor: Yong Cui, Jiangmen (CN)

() Term: 15 Years

(21) Appl. No.: 29/957,316

(22) Filed: Aug. 13, 2024

(30) Foreign Application Priority Data

Jul. 19, 2024 (CN) 202430453886.X

(51) LOC (15) Cl. 07-09

(52) U.S. Cl.

USPC D7/706; D7/501; D7/600.2

(58) Field of Classification Search

USPC D7/501, 550.1, 553.1, 553.6, 553.7,

(57) CLAIM

The ornamental design for a cup holder as shown and described.

DESCRIPTION

FIG. 1 is a perspective view of a cup holder showing my new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The dash-dash broken lines in the drawings depict portions of the cup holder that form no part of the claimed design.

1 Claim, 8 Drawing Sheets
